Primary Examiner — Karen S Acker(74) *Attorney, Agent, or Firm* — Steven H Greenfield; Greenfield Invention and Patent Consulting Inc(57) **CLAIM**
The ornamental design for an sheet with pattern, as shown and described.**DESCRIPTION**

FIG. 1 is a top plan view of the sheet with pattern according to the present invention; and,

FIG. 2 is a bottom plan view of the sheet with pattern thereof. The broken lines in the drawings represent the boundaries of the claim and form no part thereof. The dotted features within the boundaries are part of the claim.

The sheet has no appreciable thickness and the surfaces of the sheet not shown in the drawings or described in the specification form no part of the claimed design.

1 Claim, 2 Drawing Sheets**FIG. 1**

FIG. 2
